PACKARD MOTOR CAR COMPANY, OF DETROIT, MICHIGAN, A CORPORATION OF
MICHIGAN.

OIL-PUMP.

1,150,527.

Specification of Letters Patent. Patented Aug. 17, 1915.

Application filed May 19, 1909. Serial No. 497,046.

To all whom it may concern:

Be it known that I, ALLEN LOOMIS, a citizen of the United States, and resident of Detroit, in the county of Wayne and State 5 of Michigan, have invented certain new and useful Improvements in Oil-Pumps, of which the following is a specification.

This invention relates to pumps and in particular to oil pumps used in connection 10 with hydrocarbon motors and of the type described and shown in patent to Huff No. 904,434, dated November 17, 1908.

In hydrocarbon motors, particularly when used to drive motor vehicles, it is desirable to constantly feed a supply of oil to the crank case or other parts of the motor, and, as the supply necessary when the motor is running slowly is very little, some difficulty is experienced in pumping the oil in 20 quantities sufficiently small and at the same time maintaining a constant and accurate supply.

In multicylinder pumps which supply the oil to different parts of the engine mechanism, a single operating means is used to operate the several plungers or pistons, and in order that the supply delivered by each cylinder may be varied each plunger is provided with a separate adjusting means 30 whereby the movement of the plunger may be varied. Such plunger operating means usually permits the operating means to operate with considerable lost motion so that the plungers will be moved only near the ends of the reciprocation of the operating means. Therefore when the plungers are operated by a crank and a connecting rod this effective operative movement takes place at the time when the crank is near 40 dead center and therefore when the reciprocating head travels at the lowest speed. With the plungers operating at such low speed particularly when the motor is running at a low speed the supply of oil delivered is variable, especially when the parts become worn.

One of the objects of the present invention is to insure the quick reciprocation of the pump plunger regardless of the amount 50 of lost motion between the plungers and their reciprocating means.

Other objects of the invention will appear in the following description.

In the drawings: Figure 1 is a vertical 55 section through the pump embodying this

invention; Fig. 2 is an elevation of the same with one of the valves shown in section; and Fig. 3 is a detail view of the operating cam and the connecting rod.

Referring to the drawings, 10 designates 60 a fragment of a crank casing; 11 a cam shaft which is driven in a ratio of two to one from the crank shaft and having fixed to it a worm 12.

13 designates the pump casing which is 65 provided with a boss 14 extending through an aperture in the crank casing, the pump casing being provided with extensions whereby it may be bolted to the crank casing by means of bolts 14', as shown in Fig. 70 2. The shaft 15 is mounted in the pump casing and extends through the boss into the crank case. A worm wheel 16 mounted upon the shaft 15 meshes with the worm 12. A pinion 17 is secured to or integrally 75 formed with the shaft 15 and meshes with a spur gear 18 suitably secured to an operating shaft 19 which as shown in Fig. 1 is rotatably mounted in the pump casing. By means of the train of gears shown in Fig. 1 80 80 the operating shaft 19 is driven from the cam shaft 11 at a low speed.

The pump casing is provided with a number of pump chambers 20, 20 in which operate pump plungers 21, 21. These pump plungers are driven through the connecting rod 22 by means of a cam on the operating shaft 19 as hereinafter described. Adjusting screws 23, 23 permit independent adjustment of the operating strokes of the 90 plungers 21, 21.

24 designate the inlet valves, and 25 the outlet valves.

The construction of the plungers, the adjusting screws 23, 23, and the inlet and outlet valves 24, 25 is the same as in the patent referred to.

The connecting rod 22 is provided with a square opening 26 having rounded corners 27. A triangular cam 28 is eccentrically mounted upon the shaft 19 and is located within the square opening formed in the connecting rod. The triangular cam is rounded as shown and is of such a construction that the cam and connecting rod will always contact at three points.

From the above it will be seen that the connecting rod will be moved from the position shown in Figs. 2 and 3 first slightly to one side and thence downwardly by a 110

quick movement due to the eccentricity of the cam 28. Then there will be a dwell in the downward movement of the connecting rod while it is being moved to the other side; 5 then there will be a quick upward movement, and lastly a corresponding dwell as the connecting rod is being moved laterally again. Hence the up and down movement of the connecting rod will be quicker than 10 if it were mounted on a crank upon the operating shaft, and this quick movement will take place near the ends of the movement of the cam. Since the cam and connecting rod are always in engagement at at least three 15 points the cam performs the double function of an operating cam and a guiding means for the connecting rod whereby auxiliary guides are dispensed with. It is also to be noted that the velocity of the plungers will 20 be the same in both directions whereby it is insured that the proper amount of oil is drawn from the supply pipe and discharged into the discharge pipe. 25 The pump casing is provided with an opening 29 which is interiorly threaded. A threaded cap 30 screws into this opening and is provided with a flange 31. The cap is provided with an annular depression 32

for the insertion of a wrench and a plain bearing face 33 which bears against one face 30 of the gear 18. By removing the cap 30 the operating shaft 19 and the gear 18 and the cam 28, secured thereto, may be removed. Although the cam 28 is shown in the form 35 of a triangular cam it is apparent that this cam need not necessarily be of triangular construction to impart a quick movement to the connecting rod and pistons near the end of the movement of the cam and to guide the connecting rod in its movements, 40 and it is to be further understood that this invention is not to be limited to the specific construction shown and described.

What I claim is:

In a pump, in combination, a piston, an 45 operating shaft having a cam and a gear mounted thereon, a casing surrounding all of said parts, and a removable externally threaded cap constructed to screw into the casing and bear against one face of the gear. 50

In testimony whereof I affix my signature in presence of two witnesses.

ALLEN LOOMIS.
